(57) **CLAIM**

The ornamental design for a folding sofa bed, as shown and described.

DESCRIPTION

FIG. 1 is a front perspective view of a folding sofa bed, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the folding sofa of FIG.1, shown in an alternate configuration.

FIG. 10 is a perspective view of the folding sofa of FIG. 1, shown in another alternate configuration.

FIG. 11 is an enlarged detail view of area 11 in FIG. 1;

FIG. 12 is an enlarged detail view of area 12 in FIG. 2; and,

FIG. 13 is an enlarged detail view of area 13 in FIG. 2.

The broken lines in the drawings illustrate the portions of the folding sofa bed, which form no part of the claimed design. The dash-dot-dash broken lines encircling the enlarged views are for annotative purposes only and form no part of the claim thereof.

1 Claim, 13 Drawing Sheets
